UNITED STATES PATENT OFFICE.

EDWARD HEYMANN AND FRANK WM. HEYMANN, OF BOSTON, MASSACHUSETTS.

ELECTRIC-ARC LAMP.

SPECIFICATION forming part of Letters Patent No. 443,632, dated December 30, 1890.

Application filed November 5, 1888. Serial No. 290,003. (No model.)

To all whom it may concern:

Be it known that we, EDWARD HEYMANN and FRANK WM. HEYMANN, both of Boston, in the county of Suffolk and State of Massachusetts, have invented a new and useful Regulator for Arc Lamps, of which the following is a specification, reference being had to the accompanying drawings, in which—

Figures 1 and 2 are elevations of an electric lamp embodying my invention, parts being broken off in Fig. 1 for greater clearness. Fig. 3 is a plan of what is shown in Figs. 1 and 2, partly in section on lines 3 3 of Fig. 1. Fig. 4 is a sectional view, on line 4 4 of Fig. 15 3, showing a pole of the auxiliary magnet and a pole of the other magnet and also the stops hereinafter mentioned. Fig. 5 is a sectional view, on line 5 5 of Fig. 1. Fig. 6 is a view partly in section on line 6 6 of Fig. 1.

20 In all arc lamps known to us before our invention the feed-rod was connected by mechanical devices with the regulating-magnets, and the main object of our invention is to do away with mechanical devices between the 25 feed-rod and its actuating-magnet; and our invention consists, mainly, in a regulator whose feed-rod is controlled by its magnet.

In that form of our invention shown in the drawings, A is the feed-rod carrying the positive carbon and so mounted as to move lengthwise in the frame. This feed-rod A is in the field of the regulating-magnet and controlled by that magnet. As shown in the drawings, this magnet has a middle pole-piece d and 35 two terminal pole-pieces d' , from which it will be clear that the consequent pole d is opposite in polarity to the terminal poles d' , and the main windings d^2 are such as to make the terminal poles d' of the same polarity. The 40 windings d^3 are shunt-windings, and these shunt-windings d^3 oppose the main windings, as will be plain to all skilled in the art. When the carbons are in contact, the poles d and d' are at their maximum intensity, and 45 the magnet is put in motion and carries with it the feed-rod A, that feed-rod being controlled by the pole d , and the arc is thereby established. After the arc is thus established, as will be clear to all skilled in the art, the 50 magnet is affected more and more by the shunt-windings d^3 and less by the main wind-

ings d^2 as the arc increases in length, for the shunt-windings d^3 oppose the main windings d^2 , and the magnet gradually moves back on its axis as the carbon burns away, until the 55 back motion of magnet is arrested by the stops d' ; but as the carbon still continues to burn away the arc is still farther lengthened and the shunt-windings still oppose the main windings, the field of pole d will soon no 60 longer have sufficient power to prevent the feed-rod A from moving past pole d , thereby shortening the arc and regulating the feed. On the other hand, as the feed-rod A moves past its pole d , the effect of the shunt-windings d^3 decreases and the effect of the main windings d^2 increases, thereby preventing 65 further motion of the feed-rod A past pole d . If it should happen that the feed-rod moves a little too far past pole d , thereby shortening 70 the arc unduly, the magnet will take up the feed-rod slightly; but with a very nice adjustment of the shunt and main windings the motion of the magnet can be made almost imperceptible; and in practice the feed of feed- 75 rod depends mainly upon the variations of the field of force of pole d , for although the magnet can on careful inspection be seen to rock slightly, yet the length of arc does not vary perceptibly after it is once established. 80

It will be seen that the feed-rod A and its magnet are connected not by any mechanical device, as heretofore, but directly, and this is the distinguishing characteristic of our invention.

It will be obvious that our invention may be embodied in a great variety of forms, and in point of fact our main difficulty has been to select from the various forms which we have contemplated that one which we think 90 on the whole preferable. For various reasons we have concluded that the regulating-magnet should be moved upon its axis rather than in any other way and also that an auxiliary magnet is desirable for the best results; and 95 we will now describe in detail that form of our invention embodying these two features.

The poles b b' of the auxiliary magnet are of course opposite respectively to the poles d d' , and hence the main windings b^2 and shunt-windings b^3 will be understood without further description. It will be clear that the 100

poles b' serve as armatures for the poles d' and that the pole b concentrates the field of pole d .

The core D is mounted on centers, which are carried by the plates d^5 , and these plates should be adjustable on the frame. The core B is also mounted between adjustable plates b^5 ; but the core B is of course held stationary in order that the attraction between its poles b' and the poles d' of core D may give motion to core D.

The electrical connections and other details will be understood by all skilled in the art without description.

15 The feed-rod A, as will be clear, should be of iron or other magnetic material, and, therefore, close to or in easy contact with the pole d . That embodiment of our invention in which the magnet acts mechanically upon the 20 feed-rod, thereby enabling that rod to be made of non-magnetic material, forms the subject-matter of an application filed herewith.

We are aware of Patents No. 332,173, to

Wilson, December 8, 1885, No. 249,872, to Ball, November 22, 1881, No. 253,826, to Arey, 25 February 14, 1882, No. 335,786, to Telsa, February 9, 1886, and No. 362,312, to Pieper, Fils, May 3, 1887, and disclaim all that is shown in them.

What we claim as our invention is—

30 In an arc-light regulator, a feed-rod of magnetic material, in combination with an electromagnet having shunt and main windings, the core of the magnet being mounted axially and extending across the feed-rod and carrying a pole-piece the magnetism of which controls the feed-rod, and one or more pole-pieces which act with a second magnet to move the controlling-magnet on its axis, substantially as and for the purpose set forth.

EDWARD HEYMANN.
FRANK WM. HEYMANN.
